CLAIM

The ornamental design for an automotive roof tent lid, as shown and described.

DESCRIPTION

FIG. 1 is a top front left perspective view of an automotive roof tent lid showing our new design;
 FIG. 2 is a top front right perspective view thereof;
 FIG. 3 is a top rear left perspective view thereof;
 FIG. 4 is a top rear right perspective view thereof;
 FIG. 5 is a bottom front left perspective view thereof;
 FIG. 6 is a bottom front right perspective view thereof;
 FIG. 7 is a bottom rear left perspective view thereof;
 FIG. 8 is a bottom rear right perspective view thereof;
 FIG. 9 is a top view thereof;
 FIG. 10 is a bottom view thereof;
 FIG. 11 is a left side view thereof;
 FIG. 12 is a right side view thereof;
 FIG. 13 is a front view thereof; and,
 FIG. 14 is a rear view thereof.

The broken lines show portions of the automotive roof tent lid that form no part of the claimed design.
